RECEPTACLE CLOSURE AND METHOD OF
MAKING

Augustus L. Merolle, Brooklyn, N. Y.

Application March 9, 1935, Serial No. 10,135

12 Claims. (Cl. 113—121)

This invention relates to receptacle closures of the type commonly referred to as screw caps and includes novel constructions of such closures and a novel method of making the same.

5 The main object of the invention is to provide a strong, simple, efficient, reliable and inexpensively formed screw cap.

10 A further object of the invention is to provide a screw cap wherein the marginal portion of the skirt is turned inwardly and upwardly about the entire cap whereby a raw edge at the bottom of the skirt is avoided and the upper extremity of the inturned portion forms a circumferential incline adapted to operate as a thread in engagement with a thread upon the receptacle.

15 A further object of the invention is to provide a screw cap with the marginal portion of the skirt turned inwardly about the entire cap whereby a raw edge at the bottom of the skirt is avoided and 20 the upper extremity of a plurality of parts of said inturned portion has a plurality of circumferential inclines suitably distributed about the cap and adapted to co-operate with double, triple, quadruple or any desired number of threads upon the receptacle.

25 A further object of the invention is to provide a screw cap of the character as indicated wherein the inturned marginal portion has, adjacent to the entrance of the receptacle thread upon an incline, an underset lower portion overhung by an upper portion providing a recess permitting the entrance of the said thread upon the incline.

30 A further object of the invention is to increase the length of thread engaging surface of the in-turned marginal portion or portions for a given diameter of cap thereby increasing the strength and firmness of the engagement of the cap with the receptacle.

35 A further object of the invention is to provide in a cap of the character indicated beads or corrugations or both appropriately located to strengthen and stiffen the cap thereby preventing danger of distortion of the cap in its use.

40 A further object of the invention is to provide a method for manufacturing screw caps of the character as indicated.

45 Other and ancillary objects of the invention will appear hereinafter.

50 In the accompanying drawing which illustrates the invention:

Fig. 1 is a side elevation of a cap embodying the invention, partly broken away to show the interior of the cap, and the threaded neck of a receptacle upon which the cap is adapted to be screwed, the cap and receptacle being in the an-

5 gular relationship in which the cap is adapted to be applied to the receptacle and the screwing-on operation indicated;

Fig. 2 is a view of the apparatus of Fig. 1 with the cap screwed home on the receptacle, the cap being shown in radial section with the receptacle in elevation, partly broken away to show the inside of the cap;

Fig. 3 is a perspective view of the cap partly broken away and partly in section showing the 10 beginning and end of the thread engaging incline on the inturned portion of the skirt;

Fig. 4 is a side elevation of a sheet metal blank from which the cap is formed;

Fig. 5 is a side elevation of the blank at an intermediate stage of the formation of the cap;

Fig. 6 is a side elevation of the completed cap;

Fig. 7 is a section on the line 7—7 of Fig. 6;

Fig. 8 is a modified form of cap adapted for use 20 with multiple threads;

Fig. 9 is a side elevation, on an enlarged scale, of a blank from which the cap of Fig. 8 is formed;

Fig. 10 is a side elevation, partly broken away and partly in section, of a modified form of cap; and

Fig. 11 is a similar view of a further modification.

Referring to the drawing, and first to Figs. 1 to 7 inclusive, the cap comprises a top 1 and a depending marginal skirt portion 2. The marginal portion of the skirt is bent inwardly and upwardly within the skirt. This inwardly and upwardly bent portion comprises the upper portion 3 which overhangs an outwardly forced portion 4, the upper portion 5 being bent outwardly 35 and serves to space the inturned portion from the skirt. The upper extremity of the inturned portion forms a circumferential incline 6 adapted to engage beneath the receptacle thread 7 on the receptacle 8. It will be observed that the lower 40 marginal portion of the skirt is turned inwardly and upwardly throughout the entire circumference of the skirt so that no raw edges are exposed and that the incline 6 extends about the skirt for the greater part of its circumference so that 45 when applied to the receptacle 8 it will engage with substantially the whole length of the single thread 7 upon the receptacle.

In applying the cap to the receptacle, it is placed upon the receptacle in the angular relationship as indicated in Fig. 1 and the cap turned clockwise when the end 9 of the thread 7 will enter upon the incline 6 at 10 and as the turning of the cap is continued the incline 6 will wedge against the lower surface of the thread and draw 55

the top of the cap into tight engagement with the top of the neck of the receptacle. The recess formed beneath the overhanging portion 3 by the depression of the wall 4 provides a recess for receiving the receptacle thread whereby it permits it to enter upon the incline 6. When the cap has been sufficiently turned (as indicated in Fig. 2) the cap will be in closed position the clearance between the top of the receptacle neck and the top of the cap being filled by suitable sealing disc or gasket. Of course the cap, like any screw cap, will be removed by turning it in the opposite, that is a left hand, direction.

By the arrangement shown, with the recess formed beneath the part 5 by the depression of the wall 4, provision is made for the entry upon the thread incline of the closure thread notwithstanding the thread incline upon the cap (and also upon the receptacle) extends about practically the entire circumference so that a maximum thread engagement is secured and thereby the strength and security of the fastening of the cap to the receptacle is secured for a given diameter of the closure neck and cap.

The cap as just described may be manufactured by forming a sheet metal blank having the top portion 1 and the marginal depending skirt 2 the lower edges of the skirt having the circumferential incline 11 the ends of which are joined by the short steep incline 12. This marginal portion of the skirt is then bent inwardly and upwardly into the position as shown in Fig. 5 the upper part of the inturned portion being bent outwardly at 5 whereby the inner wall of the inturned portion is spaced from the outer wall of the skirt. An incline 6 at the upper extremity of the inturned portion corresponds to the incline 11 of the blank of Fig. 4, the short steep incline 13 corresponding with the incline 12. The structure of Fig. 5 then has the lower portion 4 of its inturned portion forced outwardly at 5, the upper portion 3 of the inturned portion overhanging the wall 4, thereby providing a recess beneath the part 3 for the receptacle thread as has been before referred to. The cap is then completed as shown in Fig. 6 and is the same as shown in Figs. 1, 2 and 3. It will be observed that the inwardly turned portion is bent upwardly about the circumferential line 20 whereby the lower extremity of the completed cap is substantially equi-distant from the top at all points.

While the operation of turning in the marginal edge of the skirt as shown in Fig. 5 and then forcing the wall 4 outwardly may be performed in separate operations as described the turning in of this marginal skirt portion and the depression of the wall 4 outwardly may be performed in a single operation.

Referring to Figs. 8 and 9 there is therein shown a modified form of cap embodying the invention but adapted for use with multiple threads. The blank of Fig. 9, is similar to that of Fig. 4 except that instead of a single thread engaging incline, the lower edge of the skirt has a plurality of such inclines 11' which when turned upwardly and inwardly as shown in Fig. 8 the overhanging upper portions 3' have a plurality of inclines 6' at the upper extremities of the turned over portions and the outwardly depressed walls 4' overhung by the upper portions 3' of the turned skirt portions form recesses adjacent to the entrances of the receptacle threads upon said inclines whereby the threads are permitted to enter upon those inclines. This construction, it will be observed, permits thread engaging inclines to oc-

cupy substantially the entire circumference of the skirt whereby security and strength of the engagement of the cap with the receptacle is promoted.

Fig. 10 shows a modified construction which is similar to that of Figs. 1, 2 and 3 except that the lower part of the inturned portion of the skirt together with the lower outer wall of the skirt are pushed outwardly to form an outwardly extending bead 14 which strengthens the lower portion 10 of the skirt against distortion and also provides a desirable finish for the cap. Also there may be provided adjacent the upper part of the skirt a circumferential groove 15 forming the bead 16 which strengthens the top portion of the cap 15 against distortion and also provides a pleasing finish. The bead 14 may be formed as an additional operation to those specified in connection with the formation of the cap of Figs. 1 to 3 or it may be formed in one operation with the turning 20 in of the marginal portion of the skirt.

The modification as shown in Fig. 11 is the same as shown in Fig. 10 except that the bead 16 and groove 15 are omitted and the strengthening and finish of the upper portion of the cap are provided by an externally extending bead 17 formed by the top overhanging the cylindrical walls 18 of the skirt. This bead 17 also provides a convenient finger hold in turning the cap and may if desired be provided with grooves or corrugations to facilitate the finger grip. Also the inturned portions of the cap may be stiffened and strengthened by providing corrugations 19 in the inturned portion beneath the upper portion 3'.

While the invention has been illustrated in what are considered its best applications, it may be embodied in other structures without departing from its spirit and is not therefore limited to the structures shown in the drawing.

What I claim is:

1. A closure cap comprising a top and a depending marginal skirt having marginal portions of said skirt turned inwardly and upwardly, the upper extremities of the inturned portions forming a plurality of circumferential inclinations, each of the rolls formed by the inturned marginal portions having, adjacent the beginning of the incline upon another of said portions, a lower part radially narrower than its upper part whereby said upper part radially overhangs 50 said lower part and a recess is formed permitting the entrance of the receptacle thread upon the incline of the adjacent inturned portion.

2. A closure cap comprising a top and a marginal skirt depending therefrom, said marginal skirt being bent outwardly to form a bead at the lower edge of the cap, and inwardly and upwardly inside the skirt, the upper extremity of said inturned portion being inclined circumferentially, said inturned portion having corruga- 60 tions.

3. A closure cap comprising a top and a depending marginal skirt, the marginal portion of said skirt being bent inwardly and upwardly inside the skirt with its upper extremity circumferentially inclined and corrugations in said inturned portion.

4. A closure cap comprising a top and a marginal skirt depending therefrom, said marginal skirt being bent outwardly to form a bead at the lower edge of the cap, and inwardly and upwardly inside the skirt, the upper extremity of said inturned portion being inclined circumferentially, and said top overhanging the cylindrical sides of said skirt.

5. A closure cap comprising a top and a depending marginal skirt having cylindrical walls, the marginal portion of said skirt being turned inwardly and upwardly inside the skirt and having its upper extremity circumferentially inclined, said top overhanging the cylindrical walls of said skirt.
6. A closure cap comprising a top and a marginal skirt depending therefrom having a marginal portion turned inwardly and upwardly inside the skirt with its upper extremity circumferentially inclined and said skirt having an inwardly extending bead in said skirt between the top and the inturned portion.
- 10 7. The method of making a closure cap which consists in forming a blank comprising a top and a depending marginal skirt, the lower edge of the skirt having a circumferential incline, bending the marginal portion of said skirt throughout the entire circumference of the skirt, and inwardly and upwardly within the skirt and forming a thread engaging circumferential incline at the upper extremity of said inwardly and upwardly bent portion.
- 20 8. The method of making a closure cap which consists in forming a blank comprising a top and a depending marginal skirt, the lower edge of the skirt having a circumferential incline extending about the greater part of the circumference of the skirt, bending the marginal portion of said skirt throughout the entire circumference of the skirt and inwardly and upwardly within the skirt and forming a thread engaging circumferential incline extending about the greater part of the circumference of the skirt at the upper extremity of said inwardly and upwardly bent portion.
- 25 9. The method of making a closure cap which consists in forming a blank comprising a top and a depending marginal skirt, the lower edge of the skirt having a circumferential incline, bending the marginal portion of said skirt throughout the entire circumference of the skirt, inwardly and upwardly within the skirt, bending outwardly the marginal portion of the said upwardly bent portion, and forming a thread engaging circumferential incline at the upper extremity of said inwardly and upwardly bent portion.
- 30 10. The method of making a closure cap which consists in forming a blank comprising a top and a depending marginal skirt, the lower edge of the skirt having a circumferential incline, bending the marginal portion of said skirt inwardly and upwardly within the skirt and forming a thread engaging circumferential incline at the upper extremity of said inwardly and upwardly bent portion and forcing outwardly the lower part of the said inwardly and upwardly bent portion adjacent the entrance thread upon said incline to permit the entrance of a receptacle thread upon said incline.
- 35 11. The method of making a closure cap which consists in forming a blank comprising a top and a depending marginal skirt, the lower edge of the skirt having a circumferential incline, bending the marginal portion of said skirt inwardly and upwardly within the skirt and forming a thread engaging circumferential incline at the upper extremity of said inwardly and upwardly bent portion and forcing outwardly the lower part of the said inwardly and upwardly bent portion adjacent the entrance thread upon said incline to permit the entrance of a receptacle thread upon said incline and forcing the lowermost part of said inturned portion and the adjacent external wall of the skirt outwardly to form a circumferentially extending bead at the bottom of the cap.
- 40 12. The method of making a closure cap which consists in forming a blank comprising a top and a depending marginal skirt, the lower edge of the skirt having a plurality of circumferential inclines, bending the marginal portion of the skirt inwardly and upwardly within the skirt and forming a plurality of thread engaging circumferential inclines at the upper extremity of said inwardly and upwardly bent portion and forcing outwardly the lower portion of said inturned portion adjacent the point of receptacle thread entrance of each of said inclines thereby forming recesses permitting the entrance of the receptacle threads upon the said inclines.

AUGUSTUS L. MEROLLE. 45
